UNITED STATES PATENT OFFICE

FRANK W. McDONALD, OF LAWRENCE, KANSAS

DESIGN FOR A BUILDING

Application filed June 24, 1930. Serial No. 36,155. Term of patent 7 years.

To all whom it may concern:

Be it known that I, FRANK W. McDONALD, a citizen of the United States, residing at Lawrence, in the county of Douglas and State of Kansas, have invented a new, original, and ornamental Design for Building, of which the following is a specification, reference being had to the accompanying drawing, forming part thereof.

Fig. 2 is a top plan view thereof.

I claim:

The ornamental design for a building as shown.

FRANK W. McDONALD.
